UNITED STATES PATENT OFFICE.

WILLIAM GEORGE WIESENER, OF SYDNEY, NEW SOUTH WALES, AUSTRALIA.

AUTOMATIC ZERO AND ANGLE SETTING ATTACHMENT FOR THEODOLITES AND THE
LIKE.

1,169,897.

Specification of Letters Patent.

Patented Feb. 1, 1916.

Application filed October 27, 1913. Serial No. 797,621.

To all whom it may concern:

Be it known that I, WILLIAM GEORGE WIESENER, of 334 George street, Sydney, in the State of New South Wales, in the Commonwealth of Australia, having invented certain new and useful Improvements in Automatic Zero and Angle Setting Attachments for Theodolites and the like, do hereby declare that the following is a full, clear, and exact description of the same.

This invention relates to an attachment for theodolites whereby the horizontal plate vernier is automatically set to zero, 90° or any of the other main angles on the divided circle, the object of the invention being to provide a means whereby the vernier can be set at zero or to a desired angle such as 90° with constant accuracy thus eliminating the errors in setting that are always liable to occur when the instrument has to be manipulated.

The invention consists essentially in providing one or more adjustable fixed stops either on the index plate or divided circle plate according to the design of the theodolite; and a movable stop either on the divided circle plate or index plate, said movable stop being adapted to be thrown in and out of the path of revolution of the fixed 25 stop or stops. When the movable stop is projected into the path of one of the fixed stops a spring attachment is provided to bring the two stops into close contact, and when in this position the vernier is accurately set to the division on the divided circle corresponding to the fixed stop. But in order that the invention may be more clearly understood reference will now be made to the drawings which accompany and 30 form part of this specification.

In the drawings an attachment constructed according to this invention to automatically set the zero of the A vernier to either the 360° or the 90° division on the divided circle is shown applied to a theodolite.

Figure 1, is a broken perspective view of a portion of the theodolite showing the attachment in position. Fig. 2, is a perspective view of the parts shown in Fig. 1, in an upright position and separated to show the fixed stops on the underface of the index plate. Figs. 3 and 4, are sectional elevations on planes 3-3 and 4-4 in Figs. 1 and 2 respectively. Fig. 5, is a plan view on line 5-5 Fig. 4. Fig. 6, is a detail view of the adjustable stops.

The divided circle plate 6 has on its underface a bifurcated bracket consisting of two arms 7 having hinges 8 attached to the plate 6 by screws 9. Extending from the apex of the bracket 7, as shown in Figs. 2 and 3, is a thumb-piece 11, and pivoted to the bracket 7 below the thumb-piece, is a cam lever, comprising two curved side plates 13, the cam surfaces 13^a of which are adapted to ride against the edge of the plate 6 and depress the bracket 7 when the cam lever is turned into the position shown in dotted lines in Fig. 3, the inoperative position of the cam lever being that shown in full lines in Figs. 1, 2 and 3, in which it hangs from its pivotal connection 13^b. On the bracket 7 is a vertical stop 10, see Fig. 3, adapted to be projected through an orifice in the plate 6 by means of the spring 12, and withdrawn therefrom either by a downward movement of the bracket by pressure on the thumb-piece 11, or by the turning of the cam lever from the position shown in full lines in Figs. 1 or 3 to that shown in dotted lines in the last mentioned figure. When the cam lever is turned from the position shown in full lines to the position shown in dotted lines, in Fig. 3, the cam surface 13^a engages the plate 6 and causes the downward movement of the bracket 7 which, when it has reached the limit of its lowered position, has withdrawn the stop 10 from the orifice in the plate 6. When the cam lever is turned from the position shown in dotted lines in Fig. 3 to the position shown in full lines in Figs. 1 and 3, the bracket 7 is returned to its normal position by the spring 12 to enable the stop 10 to reenter the orifice in the plate 6.

Below the index plate 14 are two adjustable stops 15 and 16 having screw-threaded shanks entered in the studs 15^a and 16^a respectively, to permit of their adjustment, for the purpose hereinafter described, the studs being fixed to the index plate 14. The free end of the stop 15 is positioned approximately beneath the B vernier and that of the stop 16 approximately 90° therefrom, and at the same radial distance from the center of the plate 14 as the stop 15.

Juxtaposed to the stop 15 and in the same horizontal plane is a projection or jaw 17 on a sliding carrier 18 having a bracket 19 on which bears a spring 20 attached to a block 21 on the index plate 14. The free end of the carrier 18 passes loosely through the flange 22 of the index plate 14 and the

lug 23 and on the end of the carrier is a cam 24. The travel of the carrier 18 is controlled by pins 25 taking in slots 26 in the carrier. When the spring 20 is drawn out 5 of action by movement of the cam lever 24 the distance between the fixed stop 15 and the jaw 17 is sufficient to allow the movable stop 10 when projected to pass easily between them, and when the spring 20 is released 10 by the downward movement of the cam lever 24 the jaw 17 bearing on the stop 10 will bring it into spring contact with the fixed stop 15 in which position the zero of the A vernier is accurately set to the 360° 15 division on the divided circle plate 6. The action of the jaw 17 in relation to the fixed stop 15 is reproduced as regards the fixed stop 16 by means of a bell crank 27 pivoted to the axis flange 14^a at 28, and having the 20 end of one arm 29 pivoted to the carrier 18 at 30, and the end of the other arm 31 which has a projection or jaw 32 juxtaposed to the fixed-stop 16.

The operation of setting the A vernier to 25 the 360° division on the divided circle is as follows:—First—using the projecting cam lever 13 as a pointer bring it to approximately the center of the B vernier. Second—project the movable stop 10 by lowering the cam lever 13. This brings the stop 10 between the fixed stop 15 and the jaw 17. Third—release the spring 19 by lowering the cam lever 24. This brings the two 30 stops into spring contact and sets the zero. The operation of setting the zero of the A 35 vernier to the 90° division is practically the same, except that the stop 10 is projected between the fixed stop 16 and the jaw 32, the approximate position to which cam lever 13 is placed in order to project the movable stop 10 between the stop 16 and the jaw 32 being indicated by a mark thus $\searrow$ on the side of the index plate.

Having now fully described and ascertained 40 the nature of my invention, what I claim as new and desire to secure by Letters Patent, is:—

1. An automatic zero and angle-setting attachment for theodolites and the like comprising, an index plate and a divided circle plate, a fixed stop on one of said plates and a movable stop on the other plate to be moved into or out of operation with the fixed stop, and a spring operated jaw in 55 juxtaposition to the fixed stop whereby it will engage the movable stop and bring it into spring contact with the fixed stop.

2. An automatic zero and angle-setting attachment for theodolites and the like comprising, an index plate and a divided circle plate, two fixed stops adjustable on one of said plates and a movable stop on the other plate to be selectively moved into or out of

operative relation with either one of the fixed stops, and two movable spring operated jaws one in juxtaposition to each of said fixed stops whereby it will engage the movable stop and bring it into spring contact with its respective fixed stop. 65

3. An automatic zero and angle-setting attachment for theodolites and the like comprising, an index plate and a divided circle plate, a fixed stop adjustable on one of said plates, a bracket hinged to the other of said plates, a movable stop pivoted to 70 said bracket to engage said fixed stop, and means for bringing said movable stop into and out of operative relation with the fixed stop. 75

4. An automatic zero and angle-setting attachment for theodolites and the like comprising, an index plate and a divided circle plate, two fixed stops adjustable on one of said plates, a bracket hinged to the other of said plates, a movable stop pivoted to 80 said bracket to engage said fixed stops, and means for bringing said movable stop into and out of operative relation with the fixed stop. 85

5. An automatic zero and angle-setting attachment for theodolites and the like comprising, an index plate and a divided circle plate, two fixed stops adjustable on one of said plates, a bracket hinged to the other of said plates, a movable stop pivoted to 90 said bracket to engage said fixed stops, and means for bringing said movable stop into and out of operative relation with the fixed stops, and two spring pressed jaws one in 95 juxtaposition to each of said fixed stops whereby it will engage the movable stop and bring it into spring contact with its respective fixed stop. 100

6. In a zero and angle-setting attachment for theodolites and the like comprising, an index plate and a divided circle plate, two fixed stops adjustable on one of said plates and a bracket hinged to the other of said plates, a cam lever pivoted to said bracket, a movable stop projecting from said lever 110 to engage with said fixed stops, a spring engaging said lever and pressing the movable stop into operative relation with the fixed stops, a thumb piece to withdraw the movable stop out of operative relation with 115 the fixed stops, spring pressed jaws in juxtaposition to the fixed jaws whereby the movable stop is brought into spring contact with the fixed stops, and a cam for controlling the movement of the spring pressed 120 jaws.
